Primary Examiner — Susan Bennett Hattan*Assistant Examiner* — Leanne Was*(74) Attorney, Agent, or Firm* — Merchant & Gould P.C.(57) **CLAIM**

The ornamental design for an entryphone, as shown and described.

DESCRIPTION

FIG. 1 is a perspective view of an entryphone showing my new design;

FIG. 2 is a front view of the entryphone shown in FIG. 1;
FIG. 3 is a rear view of the entryphone shown in FIG. 1;
FIG. 4 is a left side view of the entryphone shown in FIG. 1;
FIG. 5 is a right side view of the entryphone shown in FIG. 1;
FIG. 6 is a top view of the entryphone shown in FIG. 1; and,
FIG. 7 is a bottom view of the entryphone shown in FIG. 1.
The broken lines depict portions of the entryphone that form
no part of the claimed design.
